DESIGN FOR A LICENSE PLATE HOLDER

Robert F. Duryea, Palo Alto, Calif.

Application November 16, 1936, Serial No. 65,939

Term of patent 3½ years

To all whom it may concern:

Be it known that I, Robert F. Duryea, a citizen of the United States, residing at Palo Alto, in the county of Santa Clara and State of California, have invented a new, original, and ornamental Design for a License Plate Holder, of which the following is a specification, reference being had to the accompanying drawing, forming part thereof.

I claim:

The ornamental design for a license plate holder, as shown.

ROBERT F. DURYEA.
